(57) CLAIM

The ornamental design for pantyhose and tights, as shown and described.

DESCRIPTION

FIG. 1 is a front view of the pantyhose and tights showing my new design;

FIG. 2 is a rear view thereof;

FIG. 3 is a side view thereof;

FIG. 4 is a top view thereof; and,

FIG. 5 is a bottom view thereof.

The broken line showing of a figure and portions of the pantyhose and tights in FIGS. 1-5 are included for the purpose of showing environmental structure and portions of the pantyhose and tights that form no part of the claimed design.

A waistband is shown in a diagonal pattern.

1 Claim, 3 Drawing Sheets

FIG. 2

FIG. 3

FIG. 5
